ABSTRACT OF THE DISCLOSURE

A compact take-apart toy having a basic structure made up of a plurality of separate individual toys usable as such, the toy having a high degree of play and educational value by stimulating the child's imagination to assemble and disassemble the toy from and into the basic assembly.

SUMMARY OF INVENTION

The basic assembly or structure of my improved toy is made up of a plurality of interrelated individual toys. When assembled my toy is usable as a boat. The present invention shows the basic structure as comprising a hull also usable, when disassembled, as a sand pail or mold for sand and the like; arranged within the hull is a shovel and supported thereon is the head of a rake, the handle of which projects through an opening formed in a deck plate having a perforated surface and depending flanges embracing adjacent portions of the hull, the deck plate, when disassembled, being used as a tray or sieve for straining sand or the like; when the rake is in upright position upon the shovel and supported through the deck plate, the rake handle serves as a mast to support a sail which, when detached from such handle, may be used as a paddle or leveler for leveling sand within the sand tray or sieve.

The invention will be best understood by reference to the accompanying drawings showing the preferred form of construction, and in which:

FIG. 1 is a perspective view of the toy in its assembled condition, the toy representing a sail boat;

FIG. 2 is a sectional detail view taken substantially on line 2—2 of FIG. 1;

FIG. 3 is a sectional detail view taken substantially on line 3—3 of FIG. 1;

FIG. 4 is a perspective view of the sail detached from the rake handle, to be used as a leveler or paddle or the like;

FIG. 5 is a perspective view of the rake;

FIG. 6 is a perspective view of the deck plate, showing the same in inverted position, to be used as a sand tray or sieve;

FIG. 7 is a perspective view of a shovel;

FIG. 8 is a perspective view of the hull of the boat, to be used as a sand pail or basket or the like.

In carrying out the preferred form of construction of my invention and as before stated, the basic structure of the toy when in assembled condition is in the form of a toy boat which comprises a hull 10 having a raised bottom 11 to provide wells 13 for sand-molding purposes. The hull 10 is provided with a suitable bail or handle 14 attached to the sides of the hull 10 as at 15, so that the hull may be used as a pail or basket and carried about. When the toy is in assembled condition, the bail 14 is disposed within the hull 10, as best shown in FIG. 3.

A suitable shovel 16 is provided. This shovel 16 has a handle 16' and a blade end portion 17 which conforms to the contour of the hull 10 so that the shovel may be arranged within the hull as shown in FIG. 3, with the blade portion 17 resting on an adjacent wall 18 of the hull 10 and with the end 19 of the handle 16' rest-

2

ing upon an adjacent part 20 of the hull 10 as seen in FIG. 3.

The boat assembly further includes a deck plate 21 having on three sides thereof depending flanges 22 which embrace the upper periphery of the hull 10 at one end thereof, when the deck plate 21 is mounted over the hull in the manner shown in FIG. 1. The deck plate 21 has its flat surface perforated as seen in FIGS. 1—3 and 6, at 23. When the deck plate 21 is mounted upon the hull 10 as seen in FIG. 1, and the shovel 16 removed from within the hull 10, the deck plate 21 may be used to sift sand or the like for deposit into the hull 10. The deck plate 21 may also be removed from the hull 10 and arranged in an inverted position as shown in FIG. 6 and used as a sieve or combination scoop and sieve.

The deck plate 21 has formed therein at one edge 24 thereof, an opening 25. The handle 26 of a rake 27 is projected outwardly through this opening 25, with the head 28 of the rake supported by the shovel 16 in the manner shown in FIGS. 1 to 3 inclusive.

To the outer end portion of the handle 26 of the rake 27 is attached a sail 29. This is accomplished by projecting the end of the handle 26 through an opening provided by a U-shaped strap 30 formed in the sail 29. When the sail 29 is detached from the handle 26, it may be used as a paddle or leveler for leveling the surface of hand or other material placed within the perforated tray provided by the deck plate 21 or within the hull 10.

It is presently intended that the various components making up my improved take-apart toy are to be made of durable, non-toxic plastic material of sufficient buoyancy to permit floating of the boat in water, thus adding to the attractiveness of the toy.

Summarily, my take-apart toy, when assembled, constitutes a compact basic assembly or structure made up of a plurality of interrelated individual toys and is usable as a boat having an attractive configuration; when disassembled, such individual toys may be used as a pail or sand mold, a shovel, a sieve or tray, a rake, and a leveler or paddle. Such toy affords great amusement as well as educational value in stimulating the assembly and disassembly of the toy.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A compact take-apart like comprising a basic structure made up of a plurality of separate individual toys including

- (a) a body providing a hollow hull,
- (b) a shovel having a blade end portion corresponding to the configuration of the hull at one end thereof and supported by and within said hull,
- (c) a removable deck plate at one end of said hull and having a top perforated wall, said deck plate having an opening formed therein,
- (d) a rake having a handle removably projecting through the opening in said deck plate with the head of the rake removably supported by the shovel within the hull,
- (e) and a sail removably connected to said handle.

2. A compact take-apart toy as defined in claim 1 wherein the hull has attached thereto a bail permitting the hull to be used as a pail when the basic structure is disassembled.

3. A compact take-apart toy as defined in claim 1

wherein said deck plate on three sides thereof has depending flanges embracing the sides of the hull.

4. A compact take-apart toy as defined in claim 2 wherein said deck plate on three sides thereof has depending flanges embracing the sides of the hull.

5. A compact take-apart toy as defined in claim 1 wherein the hull has a raised bottom providing wells on opposite sides thereof for sand molding purposes.

6. A compact take-apart toy as defined in claim 1 wherein said basic structure is sufficiently buoyant to permit floating in water.
